Primary Examiner — Darlington Ly(74) *Attorney, Agent, or Firm* — Maginot, Moore & Beck LLP(57) **CLAIM**

The ornamental design for an attachment for power tool, as shown and described.

DESCRIPTION

FIG. 1 is a perspective view of an attachment for power tool showing our new design;

FIG. 2 is a right side elevational view of the attachment for power tool of FIG. 1;

FIG. 3 is a left side elevational view of the attachment for power tool of FIG. 1;

FIG. 4 is a front side elevational view of the attachment for power tool of FIG. 1;

FIG. 5 is a rear side elevational view of the attachment for power tool of FIG. 1;

FIG. 6 is a top plan view of the attachment for power tool of FIG. 1; and,

FIG. 7 is a bottom plan view of the attachment for power tool of FIG. 1.

The broken lines shown in the drawings illustrate portions of the attachment for power tool that form no part of the claimed design.
